US00D529437S

(12) **United States Design Patent** (10) **Patent No.:** **US D529,437 S**
(45) **Date of Patent:** **** Oct. 3, 2006**

(54) **BATTERY**

(75) Inventor: **Shin Miyashita**, Tokyo (JP)

(73) Assignee: **Sony Corporation**, Tokyo (JP)

(**) Term: **14 Years**

(21) Appl. No.: **29/232,922**

(22) Filed: **Jun. 27, 2005**

(30) **Foreign Application Priority Data**

Dec. 27, 2004 (JP) D2004-040019

(51) **LOC (8) Cl.** **13-02**

(52) **U.S. Cl.** **D13/103**

(58) **Field of Classification Search** D13/102-106,
D13/110, 118-119, 184; 429/96-100, 163,
429/176

See application file for complete search history.
